OFFSET DRILLING TOOL

Harry Willis Evans, Anaheim, Calif., assignor of
one-half to H. John Eastman, Long Beach,
Calif.

Application February 6, 1939, Serial No. 254,853

10 Claims.

(Cl. 255—1)

This invention relates to an offset drilling tool, by means of which the direction of a bored hole is changed in order to straighten or deflect the hole, as desired.

5 An object of my invention is to provide a novel means of setting and releasing a sleeve within the bored hole, by means of the relative longitudinal movement of a mandrel to this sleeve.

A further object is to provide a novel offset 10 drilling tool of the character stated, in which a slideable driving means is provided between the mandrel and the bit, whereby the bit may advance into the formation after the tool has been set in the hole.

15 Still another object is to provide a novel offset drilling tool, in which the releasing lug is automatically directed to releasing position on upward movement of the mandrel.

Still another object of my invention is to provide 20 a tool of the character stated, which is effective in operation and which can be easily operated by the average workman on a drilling rig.

Other objects, advantages and features of invention may appear from the accompanying drawing, the subjoined detailed description, and the appended claims.

In the drawing:

Figure 1 is a longitudinal, sectional view of 30 my offset drilling tool, with the parts in position as when the tool is being moved into the bored hole.

Figure 2 is a side elevation of my offset drilling tool with parts broken away to show interior construction, the parts being arranged as when the dog or slip is released for engagement with the side of the bored hole.

Figure 3 is a side elevation of my tool, showing 40 the parts in position for drilling forwardly in the formation.

Figure 4 is a fragmentary, longitudinal, sectional view of the sleeve, showing the slot and the cam surfaces, which guide the releasing lug into position.

45 Figure 5 is a fragmentary, side elevation of the actuating mandrel, showing the releasing lug.

Figure 6 is a sectional view taken on line 6—6 of Figure 2.

Figure 7 is a sectional view taken on line 7—7 of Figure 2.

50 Referring more particularly to the drawing, the numeral 1 indicates a sleeve, which is provided with a central bore 2, adapted to receive the mandrel 3. The mandrel 3 is slideable in the sleeve 1, and in certain positions of said

mandrel is rotatable in the sleeve. Anti-friction bearings 4—4 may be provided within the sleeve, around the mandrel 3, so that this mandrel will easily rotate in order to drill forwardly in the formation, as will be further described. The 5 mandrel 3 is provided with a releasing lug 5 on the side thereof, the purpose of which will be further described.

The sleeve 1 is provided with a vertical slot 6, which extends through the side wall of the 10 sleeve and into the bore 2. A dog or slip 7 is movably mounted in the slot 6 and is adapted to be extended or retracted into the sleeve 1 in order to non-rotatably mount the sleeve in the bored hole, or to release said sleeve for vertical 15 movement, as may be desired. A spring 8 is attached at one end to the slip 7, the other end of this spring being fixedly attached to the sleeve 1. This spring constantly urges the slip 7 into retracted position, as shown in Figure 1. The 20 slip 7 is moved outwardly into engagement with the wall of the bored hole by a cam dog 9, which is slidably mounted for vertical movement in the slot 6. A spring 10 urges the cam dog downwardly against the inner surface of the slip 7 25 for the purpose of urging this slip outwardly against the wall of the bored hole. When the slip 7 and the dog 9 are in position to extend the slip, the mandrel 3 engages the dog as shown in Figure 2 to hold the dog against the slip and thus hold this slip tightly in engagement with the wall of the bored hole.

For the purpose of directing the lug 5 into the slot 6, irrespective of the position of the lug 5, I provide a double inclined cam 11, which extends downwardly from the lower edge of the slot 6, substantially as shown in Figures 1, 2 and 4. Thus, when the mandrel 3 is pulled upwardly, the cam 11 will tend to rotate the mandrel, and direct the lug 5 into the bottom of the slot 6. A 40 roller 12 might be provided at the top of the lug 5 so that this rotating action is more easily accomplished.

A driving post 13 depends from the mandrel 3 and this driving post is preferably angular in cross-section, as shown in Figure 6, so that it is both slideable and non-rotatable in a sub 14. A head 15 on the lower end of the post limits the upward movement of the post in the sub 14. The bit 16 is mounted on the lower end of the sub 14 either directly or is coupled to the sub by the pipe 17. It is understood that the drill pipe 18 is attached to the upper end of the mandrel 3. In operation, the tool is mounted on the lower end of the drill pipe, and the weight 50 55

of the sleeve 1, sub 14, and bit 16 will hold the parts in the position shown in Figure 1, namely, with the mandrel 3 slid upwardly as far as it will move. In this top position of the mandrel, the 5 lug 5 holds the dog 9 at the top of the slot 6, thus permitting the spring 8 to force the slip 7 inwardly, permitting the tool a free passage into the bored hole. When the bottom of the hole is reached, the bit 16 rests on the bottom and 10 thereafter the operator allows the drill pipe 18 to move downwardly, thus carrying the mandrel 3 downwardly through the sleeve 1, because of the 15 slidable mounting of the post 13 in the sub 14. The dog 9 is now released and the slip 7 is pressed outwardly against the side of the 20 bored hole, as shown in Figure 3. The drill pipe 18 is now rotated, thereby rotating the bit 16 through the driving sub 14. The mandrel 3 can 25 continue to advance through the sleeve 1, and furthermore the post 13 will permit longitudinal movement of the sub 14 relative to the mandrel 3. The hole will be deflected at an angle from that previously drilled, due to the fact that the sleeve 1 is pressed to one side of the hole by the action of the slip 7. This induces a bow in the drilling string, thus deflecting the hole from the course previously drilled.

It will be noted that when the mandrel 3 moves downwardly relative to the sleeve 1, that the tapered surface of the lug 5 will force the slip 7 outwardly, thus permitting the dog 9 to drop back of this sleeve and hold the same tightly in engagement with the wall of the hole.

Having described my invention, I claim:

1. An offset drilling tool comprising a sleeve, a mandrel mounted for longitudinal movement in the sleeve, wall engaging means mounted on the sleeve and adapted when moved outwardly to engage the wall of a bored hole, means on the 40 mandrel adapted and arranged to engage the wall engaging means on longitudinal movement of said mandrel whereby said wall engaging means is urged outwardly against the wall of a bored hole, a bit operatively connected to said 45 mandrel and rotatable therewith, and means in the sleeve adapted and arranged to engage and lock said wall engaging means as said wall engaging means is pressed outwardly, whereby said wall engaging means is held in engagement with 50 the wall of a bored hole.

2. An offset drilling tool comprising a sleeve, a mandrel rotatably and slidably mounted in said sleeve, a slip mounted on the sleeve, said sleeve having a slot in the side thereof into which 55 said slip is adapted to extend, means on the mandrel extending into said slot and engageable with the slip to urge said slip outwardly, locking means in the sleeve engageable with the slip on outward movement of said slip to hold the same in extended position, cam means in the sleeve extending to said slot whereby said slip 60 engaging means is returned to said slot on upward movement of the mandrel, and a bit operatively connected to said mandrel.

3. An offset drilling tool comprising a sleeve, a mandrel rotatably and slidably mounted in said sleeve, a slip mounted on the sleeve, said sleeve having a slot in the side thereof into which said slip is adapted to extend, means on the mandrel 70 extending into said slot and engageable with the slip to urge said slip outwardly, locking means in the sleeve engageable with the slip on outward movement of said slip to hold the same in extended position, cam means in the sleeve extending to said slot whereby said slip 75 engaging

means is returned to said slot on upward movement of the mandrel, a bit mounting operatively connected to said mandrel, and a longitudinally 5 slideable driving means connecting said mandrel and the bit mounting.

4. An offset drilling tool comprising a sleeve, a mandrel slidably and rotatably mounted in said sleeve, said sleeve having a slot in the side thereof, a wall engaging slip mounted on the sleeve and extending into said slot, a lug on the mandrel engageable with the slip to extend the same, a dog mounted in said slot and engageable with the slip as the slip is extended, whereby the slip is held in extended position, and a bit 10 operatively connected to said mandrel.

5. An offset drilling tool comprising a sleeve, a mandrel slidably and rotatably mounted in said sleeve, said sleeve having a slot in the side thereof, a wall engaging slip mounted on the sleeve and extending into said slot, a lug on the mandrel engageable with the slip to extend the same, a dog mounted in said slot and engageable with the slip as the slip is extended, whereby the slip is held in extended position, a bit mounting 20 operatively connected to said mandrel, and longitudinally slideable drive means connecting said mandrel and the bit mounting.

6. An offset drilling tool comprising a sleeve, a mandrel slidably and rotatably mounted in said sleeve, said sleeve having a slot in the side thereof, a wall engaging slip mounted on the sleeve and extending into said slot, a lug on the mandrel engageable with the slip to extend the same, a dog mounted in said slot and engageable with the slip as the slip is extended, whereby the slip is held in extended position, a bit mounting 30 operatively connected to said mandrel, longitudinally slideable drive means connecting said mandrel and the bit mounting, and a cam surface in the sleeve extending to said slot whereby the lug 40 is moved into the slot on upward movement of the mandrel.

7. An offset drilling tool comprising a sleeve, a mandrel rotatably and slidably mounted in the sleeve, said sleeve having a slot in the side thereof, a slip projecting into the slot, spring means engaging the slip and urging the same into the slot, a lug on the mandrel engageable with the slip on longitudinal movement of the mandrel and urging said slip outwardly, a locking dog engageable with the slip in extended position thereof, whereby the slip is held against the wall of a bored hole, a sub, a bit mounted on the sub, a driving post depending from the mandrel, said driving post being slideable and non-rotatable in 50 the sub.

8. An offset drilling tool comprising a sleeve, a mandrel rotatably and slidably mounted in the sleeve, said sleeve having a slot in the side thereof, a slip projecting into the slot, spring means engaging the slip and urging the same into the slot, a lug on the mandrel engageable with the slip on longitudinal movement of the mandrel and urging said slip outwardly, a locking dog engageable with the slip in extended position thereof, whereby the slip is held against the wall of a bored hole, a sub, a bit mounted on the sub, a driving post depending from the mandrel, said driving post being slideable and non-rotatable in 60 the sub, and a cam surface in the sleeve extending to said slot, said cam surface guiding the lug into the slot on upward movement of the mandrel.

9. An offset drilling tool comprising a sleeve, a mandrel rotatably and slidably mounted in 70

5 said sleeve, a slip mounted on the sleeve, said sleeve having a slot in the side thereof into which said slip is adapted to extend, means on the mandrel extending into said slot and engageable with the slip to urge said slip outwardly, locking means in the sleeve engageable with the slip on outward movement of said slip to hold the same in extended position, means on the mandrel engageable with said locking means on upward movement of the mandrel, whereby said locking means is released to permit inward movement of said slip.

10 10. An offset drilling tool comprising a sleeve, a mandrel rotatably and slidably mounted in said sleeve, a slip mounted on the sleeve, said

sleeve having a slot in the side thereof into which said slip is adapted to extend, means on the mandrel extending into said slot and engageable with the slip to urge said slip outwardly, locking means on the sleeve engageable with the slip on outward movement of said slip to hold the same in extended position, means on the mandrel engageable with said locking means on upward movement of the mandrel, whereby said locking means is released to permit inward movement of said slip, cam means in the sleeve extending to said slot, whereby said slip engaging means is returned to said slot on upward movement of the mandrel.

HARRY WILLIS EVANS. 15
